CLAIM

The ornamental design for a water balloon, as shown and described.

DESCRIPTION

FIG. 1 is a perspective view of the water balloon showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is an enlarged top plan view thereof;

FIG. 7 is an enlarged bottom plan view thereof;

FIG. 8 is another perspective view thereof;

FIG. 9 is another perspective view thereof, shown in a partially-open configuration; and,

FIG. 10 is another perspective view thereof, shown in an open configuration.

The broken lines throughout the drawing figures depict portions of the water balloon that form no part of the claimed design.
